14 Claims. (Cl. 200—166)

1

This invention relates to the mounting and control of the contacts of electrical circuit-controlling apparatus such as electrical switches and circuit-breakers of all kinds but it has particular reference to the contacts of electromagnetic relays, and is more particularly concerned with the construction and control of the vibratory armature and the mounting and support of the passive or side contacts of such relays.

A fundamental problem encountered in the design of electromagnetic relays is that of preventing bouncing or chattering of the contacts, and this problem becomes more difficult of solution as the contact travel, and hence the velocity of the moving contact at the instant of impact, is increased.

Two types of bouncing may be observed, one of comparatively low frequency in which typically the first bounce occurs some one to two milliseconds after the first impact, the duration of the first break being a substantial fraction of a millisecond, and another of much higher frequency in which the contacts separate, for example, some thirty to fifty microseconds after first impact and remain separated for about half that period. The second type of bouncing can only be observed on an oscillograph having a time base scale of at least several centimeters per millisecond; its effect on the circuit operation is usually negligible but its effect on contact wear may be quite serious.

The present invention aims at eliminating both these forms of contact bouncing, and it is especially useful in relays having long contact travel, although not, of course, limited to electromagnetic relays of any kind.

In accordance with the present invention, this is attained by providing a mass mounted on one or both of the supports of the pair of contacts to be controlled in such a way as to be able to move relatively to that support due to the inertia of the mass operating at the instant of change of velocity caused by the closing of the pair of contacts and the relative movement is restrained mainly or largely by the action of forces set up by friction occurring between bearing surfaces shaped to slide smoothly one upon another or by fluid friction or by friction occurring within a deformable body. In the case of an electromagnetic relay with a vibratory armature, the inertia mass may thus be mounted on the armature or on the support or supports of the passive contact or contacts or both. The frictional forces may be exerted on a surface of the mass or within a body of deformable material coupling

2

the mass to the respective contact support so that a drag is applied to the contact support and the contacts are maintained closed in spite of any tendency to bouncing due to the elasticity of the parts.

By an electrical analogy, the frictional coupling of the inertia mass to its contact support is of the nature of resistance coupling rather than capacity coupling and the restraining force operates immediately deceleration of the contact and its support begins. The system is unlike that of a mass mounted on a compliant support and the latter would not result in the desired reduction or elimination of contact chatter.

15 If the frictional drag is exerted through an external surface of the mass, in the case of the armature contact of a relay, it may be applied to the end surface or a side surface of the armature or of a member fixed to the armature. The force holding the frictional surfaces in engagement may be provided either by a spring pressing the sliding mass against the armature or, by making the sliding mass of magnetic material, when magnetic attraction, due, for example, to stray flux from the armature, may provide the necessary force. The sliding surfaces may bear directly upon one another, or an interposed layer, such as a washer, having the desired frictional and wear-resisting characteristics may be employed, a synthetic resin impregnated with graphite or some soft metal having been found suitable. When the mass is spring-held, the spring may be made adjustable so as to control the frictional force.

20 In cases in which the velocity of transit of the armature is highly variable, and especially when it is different in the forward and return directions of its movement as in single-current working, there is some danger of the sliding mass hitting its stop, and this impact being transmitted to the armature and hence to the contacts, may itself tend to cause bouncing. In order to reduce this effect, a spring or springs may be employed tending to centralise the sliding mass with respect to its stop or stops, or the latter may be springy. Thus, for example, the spring may be a cylindrical coiled compression spring housed within the inertia mass and bearing on a seating in the mass at one end and 25 constrained by a fixed member at the other end. Then, when the mass slides relatively to the armature, the spring is deformed and in recovering, tends to centralise the mass. The fixed stop engaging one end of the spring may comprise 30 the head of a stem projecting from the arma-

ture and also passing through a clearance hole in the inertia mass and thereby acting as a limit stop for the sliding movement. Of course, other centralising means sufficiently gentle in action to permit the necessary sliding can be adopted, such as a coiled compression spring of conical configuration.

If the frictional drag is exerted within a body of rubber-like material which should exhibit considerable hysteresis, the latter is deformed on the mass tending to overshoot the armature and thereby energy is expended in the material due to its mechanical hysteresis. The body may then consist for example of a pad of soft material, such as felt or natural or artificial rubber cemented to the armature and surmounted by a metal weight forming the inertia mass and clamped between the said pad of material and a second similar outer pad of soft material. A stem may project up from the armature through the adjacent pad and passes through a clearing hole in the metal mass so that the latter overshoots the armature and deforms both resilient pads. The three layers are pressed together by a nut screwed on the outer end of the stem.

As already indicated, the passive or side contact of the relay or both of them may be also constructed to assist in the elimination of bouncing. Thus the passive contact may be carried on a stiff flat cantilever spring riveted to the frame of the relay and extending towards the armature at a suitable angle of, say, about 45 degrees. The passive contact is carried on an outer part of the arm which extends parallel to the armature face. The frictional drag or damping may be provided by employing a ring of felt or other rubber-like material encircling an extension of the said outer part of the arm so that as vibration is imparted to the cantilever arm, the said ring is deformed in compression-tension or shear and provides the damping action.

Again a pin may extend from the said extension of the outer part of the arm towards the relay frame and may itself be encircled by a ring of the deformable material enclosed in a metal ring which forms the inertia mass. In another form, the spring arm bearing the contact is extended and inclined inwards towards the relay frame at an angle and is straddled by a strip of deformable material which is encased in a metal strip which forms the inertia mass. Yet again the outer part of the contact spring arm may be shaped with a friction surface and be looped into a spring bearing the inertia mass and pressing it into contact with the said friction surface. Then on impact of the armature against the passive contact, the inertia mass is restrained by the frictional force applied to it and acts to prevent the passive contact from bounding away in front of the armature.

Furthermore, the restraining force may be provided by oil or other fluid friction.

Some examples of forms of construction in accordance with the invention will now be more fully described with reference to the accompanying drawings, in which—

Figure 1 is a side elevation of the upper part of a relay fitted with an armature damping member according to the invention;

Figure 2 is a plan of the same;

Figure 3 is an enlarged elevational, partly in section, of the upper part of the armature and its damping member;

Figure 4 is a plan of Figure 3;

Figure 5 is an elevation; and

Figure 6 is a plan corresponding respectively to Figures 3 and 4 but showing a modified form of the armature damping member;

Figure 7 is a sectional edge elevation of the upper part of an armature showing another form of the anti-bouncing device;

Figure 8 is a sectional elevation on the line VIII—VIII in Figure 9; and

Figure 9 a plan of another form of damping member employing an inertia mass including deformable rubber;

Figure 10 is a side elevation; and

Figure 11 a section on the line XI—XI in Figure 10 of one form of the improved stationary or passive contact;

Figure 12 is a side elevation; and

Figure 13 a section on the line XIII—XIII in Figure 12 of another form of stationary contact;

Figure 14 is a side elevation; and

Figure 15 a section on the line XV—XV in Figure 14 of yet a third form of stationary contact; while

Figure 16 is a side elevation; and

Figure 17 a plan of still another form of stationary contact.

Referring first to Figures 1 to 4 of the drawings, the invention is applied to an electromagnetic relay as described in the specification of my United States Patent No. 2,559,399. In Figures 1 and 2, the permanent magnets are seen at 1, the armature 2 bears the contacts 3 which engage the stationary contacts 4 supported on the frame members 5.

The inertia mass 6 carried by the armature is shown in more detail in Figures 3 and 4 and is in the form of a hollow cylinder. A screw-threaded stem 7 is adjustably tapped into the upper end of the armature 2 and is secured by a lock-nut 8 of Duralumin which consists of a hexagonal shank 9 and a flat circular platform 10. On the top of the latter is supported a washer 11 which, in this example, consists of the phenol-formaldehyde resin known as Catalin and is impregnated with graphite. The cylindrical mass 6 rests on the washer 11 and surrounds the stem 7 which passes through a clearing hole 12 in the base of the mass 6. A conical coiled compression spring 13 is housed in the cylinder 6 and abuts at the bottom on the upper surface of the base of the cylinder 6 and at the top against the head 14 of the stem 7. The spring 13 thus presses the mass 6 against the washer 11 and the latter against the platform 10 fixed to the armature 2 with an adjustable pressure. In order to adjust this pressure, the lock-nut 8 is loosened by gripping the hexagonal shank 9 and the stem 7 screwed up or down and then locked by tightening the lock-nut 8.

In operation, when the armature 2 is decelerated by one of its contacts 3 striking the coacting passive contact 4, the mass 6 tends to continue its movement thus exerting a frictional drag on the platform 10 and the armature 2, thereby resisting any tendency for the armature 2 to bounce away from the contact 4. During this time, the spring 13 is distorted but when the parts come to rest, it recovers and centralises the mass 6 again.

The mountings of the passive or side contacts 4 are as shown in more detail in Figures 10 and 11. Each contact 4 is carried on a stiff, flat cantilever spring 15 riveted to one of the relay

frame members 5 at 16. The spring 15 has parts 17 and 18 at either end parallel to the faces of the armature 2 and of the frame member 5 and an intermediate part 19 extending at an angle to the parts 17 and 18 such that the line between the contact 4 and the effective hinge at the bottom end of the part 19 is at about 45 degrees to the face of the frame member 5. The part 18 carries the stationary contact 4. The part 18 10 is extended and turned over at 21 towards the frame member 5. A strip of neoprene 22 is bent to embrace the part 21 and is retained in position by an encircling strip 23 of metal which serves as the inertia mass and when the passive contact 4 is struck, deforms the neoprene 22 so that the energy of any vibration of the spring 16 is absorbed as hysteresis in the rubber strip 22 and the vibration is immediately damped out.

In Figures 5 and 6, a modified device is shown which may replace the inertia mass 6 shown in Figures 1 to 4. Again a screw-threaded stem 7 is adjustably tapped into the end of the armature 1 and is surrounded by a washer 24 seated on the end of the armature 2, a synthetic resin washer 25, the boss of a bracket arm 26, and a further synthetic resin washer 27. This pack is adjustably pressed together by a cylindrical coiled spring 28 abutting at its lower end against a cup 29 and at its upper end against an enclosing cap 30, the whole being held down by a nut 31 screwed on to the stem 7 and enabling the pressure to be adjusted. The bracket arm 26 supports the inertia mass 32 which is a cylinder threaded over a second stem 33 and held by nuts 34.

In this case, when the armature 2 is decelerated, the mass 32 tends to continue its movement and, as a result, the bracket arm 26 exerts a frictional drag on the armature 2 through the washers 24, 25 and 27 with a similar result as in Figures 1 to 4. The actual movement of the bracket arm 26 relatively to the armature 2 in either direction is limited by a pair of stops consisting of resilient arms 35 which are secured by a further nut 36 and yield under the force of the mass 32 but recover to centralise that mass when the parts come to rest.

It is obvious that the device shown in Figures 5 and 6 could be attached to either edge surface of the armature 2 instead of to its end surface.

In the further form shown in Figure 7, a small entirely closed cylinder 53 is fixed to the top surface of the armature 2 and contains a loosely-fitting slidable piston 54 which forms the inertia mass. The spaces 55 on either side of the piston 54 are filled with light oil which provides the frictional force restraining the movement of the piston 54. Conical springs 56 at either end of the cylinder 53 serve as stops for the piston 54 and assist in centralizing the latter.

Yet another variant is shown in Figures 8 and 9 in which a stem 7 is again screw-threaded and tapped into the end of the armature 2. A circular pad 37 of felt encircles the stem 7 and rests on a washer 41 seated on the end of the armature 2. On the pad 37 rests a metal weight 38 which forms the main inertia mass and has a clearing hole 39 through which the stem 7 passes. A second pad 40 of felt rests on the weight 38 and the three members 37, 38 and 40 are pressed on to the end of the armature by a top washer 41a and nuts 42, the pad 37 being preferably cemented to the washer 41 and to the weight 38 and the pad 40 also being cemented to the weight 38. In this case, when the armature is

decelerated, the weight 38 continues its movement but there is no frictional sliding of one member on another. On the other hand, the pads 37 and 40 are deformed with internal friction which restrains the motion of the weight 38 and thus prevents bouncing of the contacts.

In Figures 12 and 13, a variant of the mounting for the stationary contacts is shown. The contact 4 is mounted on a cantilever spring 15 10 as in Figure 10 but the part 18 of the spring is extended and is encircled by a relatively massive ring 43 of felt. The effect, however, is similar to that of the form shown in Figures 10 and 11.

In Figures 14 and 15, the mounting for the stationary contacts is yet again varied. In this case, the part 18 of the cantilever spring 15 has a headed pin 44 extending at right angles towards the relay frame member 5. A ring of felt 45 encircles the pin 44 to which it is fixed by adhesive and the ring 45 is encased in a metal ring 46 which acts as the inertia mass. Otherwise, the operation is the same as in the case of Figures 10 and 11.

Finally, in Figures 16 and 17, the part 18 of the cantilever spring 15 which bears the stationary contact 4 is turned at right angles at 47 into the vertical plane and broadened into a platform 48. A narrow extension 49 is looped to the side at 50 and turned over into contact with the platform 48 at 51. At that point, it carries the inertia mass 52 which is a cylindrical weight. The spring loop 50 is set so that it causes the mass 52 to be frictionally coupled to the contact 4 through the platform 48 on the supporting arm 18.

What I claim is:

1. In an electric switch having a pair of co-operating contacts, one of which is mounted upon a movable support, the combination of an inertia member mounted upon said movable support and being movable with respect to said support under the impact of a sudden engagement of said contacts, means providing a frictional coupling between said inertia member and said support for applying frictional drag on said support by the relative movement of said inertia member upon sudden closing of said contacts, and resilient means interposed between said inertia member and said support and tending to limit said relative movement.

2. A switch according to claim 1 wherein said movable support comprises an armature member carrying the movable contact.

3. A switch structure according to claim 1 wherein said movable support comprises a yieldable member carrying a passive contact.

4. A switch structure according to claim 1 wherein said frictional coupling is provided by sliding contact between a surface of said inertia member and a surface on said movable support, and including spring means for holding said surfaces in contact under pressure.

5. A switch structure according to claim 4 and including a graphite-impregnated washer interposed between said surfaces.

6. A switch structure according to claim 1 wherein said frictional coupling means comprises a body of deformable material connecting said inertia member with said movable support and having appreciable internal resistance.

7. A switch structure according to claim 1 wherein said inertia member comprises a body of deformable material mounted upon said movable support and being connected with said support by a resilient portion thereof having an appreciable internal resistance.

able internal resistance, whereby said resilient portion forms a frictional coupling between said body and said support and opposes relative movement between said body and said support.

8. An electric switch structure according to claim 1 and including a fixed stop for limiting relative movement of said inertia member with respect to said support, and wherein said resilient means acts upon said inertia member in a direction to oppose movement of said member towards said stop.

9. In an electric switch having a movable contact carried by a movable armature and a passive contact supported upon a cantilever spring and being yieldably movable upon engagement by said movable contact, the combination of an inertia member supported upon said cantilever spring and being movable with respect to said spring under the impact of sudden engagement of said contacts, and means providing a frictional coupling between said inertia member and said spring for applying a frictional drag on said spring by the relative movement of said inertia member.

10. A switch structure according to claim 9 wherein said inertia member comprises a body of resilient deformable material mounted on an extension of said spring.

11. A switch structure according to claim 10 and including a metal member surrounding said body of deformable material.

12. A switch structure according to claim 9 wherein said inertia member is carried by an ex-

10 tension arm of the cantilever spring turned back so that the inertia member is pressed to bear frictionally on the cantilever spring.

13. An electric switch structure according to claim 1 wherein said inertia member is mounted upon said movable support by a stem projecting from said support and passing through an enlarged opening in said member, and said resilient means comprises a conical coil spring surrounding said stem and engaging said inertia member to yieldably hold said member in a position with the said opening in concentric relation with said stem.

14. A switch structure according to claim 1 wherein said frictional coupling means comprises a lever arm carrying said inertia member on one end thereof and means securing the other end of said arm to said movable support for pivotal movement about an axis arranged transversely of said arm.
